[57] CLAIM

The ornamental design for a mobile golf club carrier, as shown.

DESCRIPTION

FIG. 1 is a perspective view of a mobile golf club carrier showing the rear and one side of my new design; FIG. 2 is an enlarged perspective view thereof in collapsed condition showing the front and side disclosed in FIG. 1;

FIG. 3 is an enlarged perspective view thereof in collapsed condition showing the rear and side opposite to that shown in FIG. 1; and

FIG. 4 is a perspective view thereof showing the front and side shown in FIG. 1.

FIG. 4
